(57) **CLAIM**

The ornamental design for a footwear with a reel based closure device substantially as shown and described.

DESCRIPTION

FIG. 1 is a perspective view of a footwear with a reel based closure device;

FIG. 2 is a front view of the footwear with a reel based closure device;

FIG. 3 is a back view of the footwear with a reel based closure device;

FIG. 4 is a first side view of the footwear with a reel based closure device;

FIG. 5 is a second side view of the footwear with a reel based closure device;

FIG. 6 is a top view of the footwear with a reel based closure device; and,

FIG. 7 is a bottom view of the footwear with a reel based closure device.

The broken lines in the drawings depict portions of footwear with a reel based closure device and form no part of the claimed design.

1 Claim, 7 Drawing Sheets
